UNITED STATES PATENT OFFICE

ROBERT H. KING, OF CLEVELAND HEIGHTS, OHIO, ASSIGNOR TO THE ROTOR AIR TOOL COMPANY, OF CLEVELAND, OHIO, A CORPORATION OF OHIO

ROTARY MOTOR TOOL

Application filed January 31, 1930. Serial No. 424,981.

This invention relates to a rotary motor tool and particularly to such a tool adapted for buffing, grinding, or like purposes.

The main object of the invention is to provide a rotary motor tool of this character wherein the parts are so constructed and arranged that the handles may be positioned relatively near the plane of the tool proper to thereby effect stability of operation of the rotary motor tool, thus increasing the efficiency thereof and improving the control and operation of the same.

A further object is to arrange in an efficient manner the reduction gearing, valve, handles, and inlet and exhaust passageways so as to avoid manufacturing complications, and to provide ease of operation of the valve and at the same time admit of the use of reduction gearing, and a housing enclosing the same which adds little to the size of the structure as a whole.

A still further object is to provide a rotary motor tool of this character which is compact and yet relatively powerful in operation for its size.

The above and other objects are attained by my invention which may be here briefly summarized as consisting in certain novel details of construction and combinations and arrangements of parts which will be described in the specification and set forth in the appended claims.

In the accompanying sheets of drawings illustrating an embodiment of my invention, Fig. 1 is a plan view of a rotary motor tool; Fig. 2 is a longitudinal sectional view taken on line 2—2 of Fig. 1, looking in the direction of the arrows; Fig. 3 is a fragmentary sectional view taken on line 3—3 of Fig. 1, looking in the direction of the arrows; and Fig. 4 is a horizontal sectional view taken approximately on line 4—4 of Fig. 2 looking in the direction of the arrows.

Referring now to the drawings and first to the main or general construction, it will be seen that the rotary motor tool herein illustrated comprises a motor housing 10, a gear housing 11, a plate 12 arranged between the two housings, a live handle 13 secured to the motor housing and the gear

reduction housing, and a dead handle 14 secured to the gear reduction housing and extending at right angles to the live handle 13. The motor housing 10 is substantially circular in shape and is provided with an extension 15 which can be called the inlet extension and an extension 16 which can be called the outlet extension, the housing and the extensions being cored out so that a cylinder 17 can be pressed into the housing and held in position by shoulders 18 engaging the cylinder adjacent its opposite ends. The cylinder 17 divides the interior of the housing into two chambers, namely, an inlet chamber 19 and an exhaust chamber 20. The inlet chamber 19 is an elongated vertical chamber formed by the inward extensions 21 of the inlet extension 15 and the cylinder 17, this chamber 19 communicating adjacent its lower end with a duct 22 extending through the inlet extension 15. The exhaust chamber 20 is arcuate in shape and extends longitudinally of the cylinder 17, such exhaust chamber also having outwardly extending portions 23 at its opposite ends and arranged on opposite sides of the inward extensions 21 (see Fig. 4) and connected above the duct 22 by a passage 24 (see Fig. 2) thus forming a continuous chamber.

In addition to the support for the cylinder provided by the shoulders 18 and the ends of the extensions 21, a pair of inwardly projecting ribs 25 and 26 are arranged in the exhaust chamber and are coextensive with the cylinder 17. The rib 25 is provided with a small opening 27, while the rib 26 is of greater width than the rib 25 and is provided with a cored portion to provide communication between the parts of the exhaust chamber and also has a pin 28 extending inwardly through the motor housing and engaging a keyway 29 in the cylinder 17 to prevent rotation of the latter. The exhaust chamber 20 communicates with a passage 30 in the exhaust extension 16, such passage being enlarged adjacent its outer end and threaded to receive a threaded fitting 31 to which a hose may be fitted to carry away the exhaust fluid, if desirable.

It will be observed that while the rib 26 is cored out to provide communication between the parts of the exhaust chamber 20, the rib 25 is provided also with a single small opening 27 which effects communication between the parts of exhaust chamber 20 to allow the escape of a small portion of the exhausted fluid. It will be noted that the exhausted fluid which travels through the exhaust chamber 20 in an anti-clockwise direction, as viewed in Fig. 4, will pass through the opening 24 and into the extended portion 23 of the exhaust chamber which is adjacent the passage 30, thus providing a sufficiently tortuous passage to effect a muffling of the exhaust fluid. The importance of this muffling arrangement will be appreciated when it is realized that a rotary motor tool of this character is noisy in operation when the exhaust fluid escapes in a direct way and also that the use of a separate muffling device would materially increase the weight and size of the tool.

The outer end of the cylinder 17 is closed by means of a plate 32 arranged in the housing and machined to fit such end of the cylinder accurately to thereby seal the same. The other end of the cylinder 17 is closed by the plate 12 arranged between the motor housing 10 and the gear reduction housing 11, this plate likewise being accurately machined so as to effect an efficient seal for the end of the cylinder. The plate 12 and the plate 32 are provided with aligned openings eccentrically arranged with respect to the cylinder 17 for the purpose of allowing the motor spindle 33 to pass therethrough, the openings being of such size as to provide a slight clearance between the plates 12 and 32 and the spindle 33. A ball bearing 34 is arranged in the housing 10 above the plate 32 and in such bearing a reduced end 35 of the motor spindle 33 is journaled. The end of the motor housing 10 is provided with an opening to facilitate the machining of the housing, which opening is closed by a threaded cap 36, such cap having a threaded opening for the purpose of supplying lubricant to the tool, this last opening in turn being closed by a threaded plug 37. The lower portion of the motor spindle 33, as viewed in Fig. 2, is provided with a pinion 38 and with a reduced end 39 journaled in a ball bearing 40 arranged in a manner later to be referred to.

The motor housing 10, the gear reduction housing 11 and the plate 12 arranged therebetween are assembled together by means of a series of bolts 41 extending through a flange of the gear reduction housing and the plate 12 into threaded openings in the motor housing 10. The lower end of the gear reduction housing 11, as viewed in Fig. 2, is reduced and has arranged therein a pair of ball bearings 42 held in separated rela-

tionship by an inwardly extending shoulder 43. Arranged in these bearings is a tool spindle 44 the inner end of which is enlarged to form the gear 45, while the lower end of the spindle 44 is threaded, as indicated at 46 in Fig. 2, to receive the tool. The lower end of the reduced portion of the gear reduction housing is externally threaded to receive the internally threaded packing nut 47 which holds in position packing 48 the purpose of which is to prevent lubricant from escaping from the gear reduction housing and prevents dirt from entering the housing from the exterior. A spacing sleeve 49 is threaded on the tool spindle 44 and projects outwardly of the housing through an opening in the packing nut 47 while a second spacing sleeve 50 surrounds the spindle 44 between the bearings 42. When the tool (not shown) is secured to the tool spindle 44, it will abut the end of the sleeve 49 and the pressure of the tool will be transmitted through the lower bearing 42 against the inwardly extending shoulder 43.

The gear 45 is provided with a centrally arranged countersink within which is the ball bearing 40 above referred to receiving the reduced end 39 of the motor spindle 33, thus allowing the gear 45 and the motor spindle 33 to rotate freely without any driving connection between the same and to provide a supporting relation between the tool spindle and the motor spindle. The under side of the plate 12, as viewed in Fig. 2, is provided with a downwardly extending annular rib 52 forming an annular recess 51 receiving a ball bearing 53. The recess 51 formed by the annular rib 52 is in alignment with an oppositely disposed recess 54 formed in the gear reduction housing 11 and likewise receiving a ball bearing 55. A shaft 56 having its opposite ends journaled in the bearings 53 and 55 is provided with a gear 57 and a pinion 58 integrally formed therewith, the gear 57 meshing with the pinion 38 on the motor spindle 33 and the pinion 58 meshing with the gear 45 on the tool spindle 44.

The live handle 13 is connected with the motor housing and the gear reduction housing by means of a connecting bracket 59 secured to such housings by a series of bolts 60 (see Figs. 1, 2 and 4). The bracket 59 has an air duct 61 extending therethrough and communicating at one end with the duct 22 through the extension 15 of the motor housing and at its other end with an opening 62 formed in the bracket and extending laterally outwardly thereof through an extension 63 formed on the bracket. The extension 63 is internally threaded to receive a threaded bushing 64 which is permanently connected with the bracket by means of dowels 65. The handle 13 includes a relatively elong-

gated body 66 having a reduced threaded end 67 fitting within the internally threaded bore of the bushing 64, such body also having a central bore 68 extending therethrough and provided with an enlarged portion 69. The outer end of the body 66 is externally threaded to receive an internally threaded nut 70 which in turn is provided with a threaded opening to receive a fitting 71. 5 The body 66 is likewise provided with a slot 72 extending therethrough and communicating with the enlarged portion 69 of the bore 68, such enlarged portion of the bore having a substantially cylindrical slidable valve member 73 arranged therein and carrying at its outer reduced end 74 a head 75 in the form of a poppet valve. The sliding valve member 73 adjacent the reduced portion 74 is provided with two longitudinally extending 10 passageways 76 communicating with a semi-circular passageway 77 located substantially at the middle portion of the sliding valve member. The inner end of the sliding valve member is provided with a bore 78 communicating with the semi-circular passageway 77 and with the bore 68 through the body 66. A screwpin 79 is secured to the sliding valve member and extends outwardly through the slot 72 in the 15 body 66 and into a diagonally arranged slot 80 formed in a sleeve 81 arranged on the body 66 between an annular shoulder 82 and the inner end of the nut 70 so that when the 20 sleeve is rotated the screw-pin 79 and the valve member 73 to which it is attached will be moved in the enlarged portion 69 of the bore 68 through the body 66 by the engagement of the walls of the diagonal slot 80 with the pin 79. A split ferrule 83 is arranged 25 in a circular recess of the sleeve 81 so as to cover the diagonal slot 80 and screw pin 79 to prevent the entrance of dirt into the passageway into the bore through the body 66. Thus it will be seen that when the 30 sleeve 81 is rotated in the proper direction, the head or poppet valve 75 will be unseated and fluid may pass into the enlarged portion 69 of the bore around the reduced end 74 of the sliding valve member through 35 the passageways 76 and 77 into the bore 78 of the valve member and thence into the bore 68 of the body, from which it passes through the opening 62 into the ducts 61 and 22 of the bracket 59 and motor housing 50 40 and 22 of the bracket 59 and motor housing 55 45 10 respectively into the inlet chamber 19.

The cylinder 17 is provided with a series of diagonally extending openings 84 arranged longitudinally of the cylinder and communicating with the intake chamber 19 (see Figs. 2 and 4), thus allowing the fluid in the intake chamber to pass into the interior of the cylinder 17. The rotor 85 is arranged in the cylinder and is keyed to the motor spindle 33, which spindle, as has been 50 previously mentioned, is eccentrically dis-

posed with respect to the cylinder. The rotor 85 is provided with a number of guideways 86, in this instance three, extending radially inwardly of the rotor and spaced circumferentially thereof. In each of these guideways is arranged a slidable blade 87 the outer edge of such blade contacting with the inner surface of the cylinder throughout the longitudinal length of such edge and also having a sealing contact with the plates 70 12 and 32 at the opposite ends of the cylinder. In addition to the openings 84, the cylinder 17 is provided with a plurality of longitudinal rows of openings 88 communicating with the exhaust chamber 20. 75 80

From the foregoing description, it will be clear that the fluid entering the cylinder through the diagonal openings 84, as viewed in Fig. 4, will strike against the lowermost blade 87 and will cause the rotor to rotate 85 in a clockwise direction until the blade has nearly reached the first row of exhaust openings 88, at which time the next succeeding blade will have passed the inlet openings 84, whereupon the fluid which has moved 90 the first named blade will be free to pass through the exhaust openings into the exhaust chamber 20, while fresh fluid entering the cylinder through the inlet opening 84 will cause the second mentioned blade to 95 move around in the same manner as the first mentioned blade.

Since the rotor is keyed to the motor 100 spindle 33, the rotation of such rotor will rotate the spindle and the pinion 38, such pinion in turn driving the gear and pinion 57 and 58, with the pinion 58 driving the gear 45 and the tool spindle 44.

A boss 89 (see Figs. 1 and 3) projects 105 from the gear housing 10 below the top of such housing and substantially at right angles to the extension 63 of the bracket 59 with the horizontal center lines of the extension and the boss in the same plane. The boss 89 is provided with a threaded recess within which a bushing 90 is arranged and permanently secured while the handle 14 is detachably connected to the bushing by screwing the threaded reduced end 91 of the handle into the bushing. The handle is also provided with a number of flats 92 to facilitate its application to or removal from the machine. 110 115

It will be noted that the live handle 13 and the dead handle 14, while arranged substantially at right angles to each other, lie in the same plane, which plane is relatively near the outer end of the tool spindle 44 to which the tool is to be attached. It will be appreciated that this arrangement stabilizes 120 the rotary motor tool in operation since it increases the ease and steadiness with which the tool may be controlled. In tools of this type where the handles are arranged at a point relatively remote from the outer end 125 130

of the tool spindle, the operation of the tool causes the rotary motor tool as a whole to wobble to a certain extent, thereby making it difficult to hold the tool in close contact with the work while exerting pressure to the tool through the handles. On the other hand, with the handles arranged relatively near the outer end of the tool spindle, the operator will be able to exert pressure to the tool through the handles and to effectively control the rotary motor tool as a whole since the tendency thereof to wobble is substantially eliminated, thus enabling the operator to more efficiently operate the tool and to perform the work desired. This is especially true when an abrasive or grinding wheel is secured on the tool spindle and the rotary motor tool is used as a facing tool. In specifying in the description and claims that the handles are arranged relatively near the outer end of the tool spindle, it is meant that the handles are located nearer to the tool or working end than they are to the opposite end of the rotary motor tool as a whole.

While I have shown the preferred construction and one which operates with high efficiency, I do not desire to be confined to the precise details shown but aim in my claims to cover all modifications which do not involve a departure from the spirit and scope of the invention.

I claim:

1. In a rotary motor tool, a motor including a housing and a motor spindle, a tool spindle axially aligned with said motor spindle, reduction gearing between said spindles, a housing for said gearing and tool spindle, a bracket secured to both housings, a handle projecting from said bracket, and a second handle extending from the second named housing, both handles lying in a common plane at right angles to one another and perpendicular to the axis of the tool spindle.

2. In a rotary motor tool, a motor including a housing having a passageway leading to the motor and a motor spindle, a tool spindle axially aligned with said motor spindle, reduction gearing between said spindles, a housing for said gearing and tool spindle, a bracket secured to both housings and having a passageway communicating with the passageway in the motor housing, a handle projecting from said bracket and having a passageway communicating with the passageway therein, and a second handle extending from the second named housing, both handles lying in a common plane at right angles to one another and perpendicular to the axis of the tool spindle.

3. In a rotary motor tool, a motor housing and a gear housing, a tool spindle and reduction gearing supported in said gear housing, a motor spindle axially aligned with

said tool spindle and having one end supported in said motor housing and its other end supported by said tool spindle and operatively connected with said reduction gearing, a bracket connected to both housings, a handle projecting from said bracket, a second handle projecting from said gear housing, both of said handles lying in a common plane at right angles to one another and perpendicular to the axis of the tool spindle.

In testimony whereof, I hereunto affix my signature.

ROBERT H. KING.
